DON D. MYERS, OF TOLEDO, OHIO

LOOSE-LEAF BINDER AND METHOD OF MANUFACTURING THE SAME

Application filed March 14, 1928. Serial No. 261,549.

This invention relates to a new and improved loose leaf binder and the method of manufacturing the same with particular reference to the type of loose leaf binder in which split rings are used as the leaf-retaining members.

In binders of this character hitherto known to the art the final assembly of different parts of the binder and particularly the final assembly of the ring-carrying plates has been difficult to accomplish and the choice of stop members for controlling the movement of the ring-carrying plates has been limited.

The main object of my invention is to provide a book of this character having ring-carrying plates of such a design that they may be assembled into the book after all of the other mechanism of the book has been fixed in position. Another object is to provide a book in which the stop members for limiting the upward movement of the ring-carrying plates may be rigidly affixed to the back plate of the book.

Another object is to provide a book in which the ring-carrying plates may be assembled and from which they may be disassembled without the necessity of assembling or disassembling any other part of the mechanism.

Other objects and advantages relate to the size, shape and arrangement of parts as will more fully appear from the following description taken in connection with the accompanying drawings in which:

Figure 1 is a perspective view partially broken away of my assembled book in the open position.

Figure 2 is a top view of my ring assembly locked in position.

Figure 3 is a top view of my ring assembly in the unlocked position.

Figure 4 is a section on line 4-4 of Figure 2.

Figure 5 is a section on line 5-5 of Figure 2.

Figure 6 is a section on line 6-6 of Figure 2.

Figure 7 is a perspective view of the male ring-carrying plate.

Figure 8 is a perspective view of the female 50 ring-carrying plate.

My device consists of covers —1— and —2— joined together by a concave back section —3— to which is rigidly affixed by clamps —30— or other convenient means, 55 a spring back plate —4— concave in cross-section and being returned bent at each longitudinal edge to form slots —5— and —6— for a purpose hereinafter to be described. Vertical stop members —7— and —8— are rigidly affixed in back plate —4— at opposite ends thereof for a purpose hereinafter to be described. Members —7— and —8— are similar in shape and, as perhaps may best be seen from Figure 6, each consist 65 of a shank —9— and a cross-head —10—.

I also provide a male ring-carrying plate —11— which carries on its inner edge a plurality of downwardly inclined tongues —12— and a plurality of intermediate upwardly 70 inclined tongues —13—. I also provide on the inner edge of plate —11— an outwardly extending locking tongue —14—. One end of the inner edge of plate —11— is cut away to form a shoulder —15— and the opposite 75 end of plate —11— is cut away to form a slot —16— with a shoulder —17— in one edge thereof. Plate —11— also carries a plurality of apertures —18— adjacent the inner edge thereof into which are placed 80 male half-rings —19— secured in position by riveting, as perhaps may best be seen at 20 on Figure 6.

Female ring carrying plate —21— is provided on its inner edge with a keeper slot 85 —22— adapted to co-act with locking tongue —14—. Plate —21— is cut away at one end of the inner edge to form a shoulder —23— and is provided at the other end of the inner edge with a slot —24— and a shoulder —25— 90

adjacent one side of slot —24—. Plate —21— is also provided with a plurality of apertures —26— for the reception of female half-rings —27— secured in place by riveting, as perhaps may best be seen at 28 in Figure 6. Male half-rings —19— and female half-rings —27— are so positioned respectively in plates —11— and —21— that when plates 11 and 21 are in the locked position the opposed half-rings —19— and —27— will register with each other.

The method of assembling back plates —11— and —21— onto back plate —4—, as perhaps may best be seen from Figures 2 and 15 3, is as follows; I place member —11— with its rear longitudinal edge in slot —6— of the back plate —4— and with slot —16— registered with cross-head —10— of stop member —8—, as perhaps may best be seen in Figure 20 3. In this position shoulder —15— will be against the inner side of cross-head —10— of stop member —7— so that stop members —7— and —8— will not be in the path of vertical movement of the inner edge of plate 25 —11—. I then place the rear longitudinal edge of plate —21— in slot —5— of back plate —4— with slot —24— of plate —21— registered with cross-head —10— of stop member —7— and with shoulder —23— adjacent the inner side of stop member —8—. I then insert the forward edge of plate —21— between the tongues 12—12 and 13—13 of plate —11— with locking tongue —14— on the under surface of plate —21— adjacent 30 keeper slot —22—. I then depress plates —11— and —21— against the spring action of back plate —4— and locking tongue —14— until the upper surfaces of plates —11— and —21— are beneath the under surfaces of 35 crossheads —10— of stop members —7— and —8—. I then move plates —11— and —21— longitudinally in relation to each other so that shoulder —17— of plate —11— will be positioned underneath cross-head —10— of 40 stop member —8— and shoulder —15— of plate —11— will be positioned under cross-head —10— of stop member —7— and shoulder —23— of plate —21— will be positioned under cross-head —10— of stop member —8— 45 and shoulder —25— of plate —21— will be positioned under cross-head —10— of stop member —7—. This movement will bring locking tongue —14— into registration with keeper slot —22— so that it is allowed to 50 spring upward into keeper slot —22— to prevent any longitudinal movement of plates —11— and —21— in relation to each other.

The combined widths of plates —11— and —21— is such, with relation to back plate 55 —4—, that a vertical movement either upward or downward of plates —11— and —21— may be accomplished only by overcoming the yielding resistance offered by back member —4— so that in either the raised 60 or lowered position plates —11— and —21—

will be yieldingly held in that position by back member —4—. The downward movement of plates —11— and —21— is limited by back plate —4— and the upward movement of plates —11— and —21— is limited by 70 cross-heads 10—10 of stop members —7— and —8—.

Male split rings —19— and female split rings —27— are so positioned in relation to plates —11— and —21— and to each other 75 that when plates —11— and —21— are in the down position the prong —29— of male half ring —19—, shown in dotted lines on Figure 5, will enter the V-slot, not shown, on the end of half ring —27— to form a complete ring as may best be seen in Figure 6. When plates —11— and —21— are in the raised position, as perhaps may best be seen from dotted lines in Figure 5, half rings —19— and —27— will be separated from 80 each other to permit the insertion thereon of leaves, not shown, as desired.

It will be understood that in the upward and downward movement of plates —11— and —21— they will remain in pivotal relation to each other due to the fact that the inner longitudinal edge of plate —21— is movably held between tongues 12—12 and 13—13.

If it is desired to remove plates —11— and —21— from back plate —4— locking tongue —14— is depressed beneath plate —21— to permit the longitudinal movement of plates —11— and —21— in relation to each other so that they may be withdrawn from registration with the under surfaces of cross-heads —10—10 of stop members —7— and —8— into the position shown in Figure 3 and when in this position they may be removed from back plate —4— and from registration with 105 each other.

In order to explain my device and the method of manufacturing and assembling the same I have shown and described a specific structure and form of part as an exemplification of an embodiment of my invention, but I do not desire to restrict myself to the exact shape, form or relation of parts as various changes may be made within the scope of the appended claims.

What I claim is:

1. The method of manufacturing a device of the class described consisting of forming a book body comprising opposed covers connected by a back portion, rigidly affixing on 120 the back portion a spring back plate having stop posts having crossheads in spaced relation rigidly affixed thereto, forming ring-carrying plates having means on their inner longitudinal edges whereby they may be retained in pivotal relation with each other, and each ring-carrying plate also having on 125 its inner longitudinal edge a slot adapted to receive a portion of the crosshead of one of said stop posts, placing the outer longitudinal 130

edges of the ring-carrying plates in opposite edges of the spring plate with the slots before mentioned in registration with the respective stop posts, depressing said ring-carrying plates beneath the crossheads of the stop posts, and moving the ring-carrying plates longitudinally in relation to each other whereby the said slots are moved out of registration with the locking portions of the stop posts and the opposite ends of the plates are each moved beneath the cross-head of a stop post for retaining the ring-carrying plates in position.

2. The method of manufacturing a device of the class described consisting of forming a book body comprising opposed covers connected by a back portion, rigidly affixing on the back portion a spring plate having stop posts, each post comprising a shank and an offset locking portion, forming ring-carrying plates, forming on one of said plates on its inner longitudinal edge alternately raised and depressed tongues for receiving and retaining in pivotal relation the inner edge of the other ring-carrying plate, forming in the inner longitudinal edge of each of said ring-carrying plates at one end thereof a slot having an adjacent shoulder, and forming a shoulder at the other end of each plate, placing the outer longitudinal edges of the ring-carrying plates in opposite edges of the spring back plate with one of said slots in registration with one stop post and the other slot in registration with the other stop post, depressing said ring-carrying plates beneath the locking portion of the stop posts and moving the ring-carrying plates longitudinally in relation to each other whereby the said slots are moved out of registration with the stop posts and the said shoulders are moved into registration with the locking portions of the stop posts for retaining the ring-carrying plates in position.

3. The method of manufacturing a device of the class described consisting of forming a book body comprising opposed covers connected by a back portion, rigidly affixing on the back portion a spring plate having stop posts, each post comprising a shank and an offset locking portion, forming ring-carrying plates, forming on one of said plates on its inner longitudinal edge alternately raised and depressed tongues for receiving and retaining in pivotal relation the inner edge of the other ring-carrying plate, forming in the inner longitudinal edge of each of said ring-carrying plates at one end thereof a slot having an adjacent shoulder and forming a shoulder at the other end of each plate, forming on the inner edge of one of said ring-carrying plates an outwardly extending locking tongue, and forming on the inner edge of the other ring-carrying plate a keeper slot for the reception of said locking tongue, placing the outer longitudinal edges of the ring-

carrying plates in opposite edges of the spring back plate with both of the slots before mentioned in registration with a stop post and with the locking tongue out of registration with the keeper slot, depressing said ring-carrying plates beneath the locking portion of the stop posts, and moving the ring-carrying plates longitudinally in relation to each other whereby the said slots are moved out of registration with the stop posts, the shoulders moved into registration with the locking portion of the stop posts for retaining the ring-carrying plates in position, and the locking tongue moved into registration with the keeper slot for preventing longitudinal movement of the ring-carrying plates in relation to each other.

4. In a device of the class described, opposed covers, a back portion connecting said covers, a spring back plate rigidly secured to said back portion, stop posts having crossheads rigidly secured in the opposite ends of said spring back plate, a pair of ring-carrying plates each having on its inner longitudinal edge adjacent one end thereof a slot adapted to permit the passage therethrough of a portion of a cross-head on a stop post, means on the inner longitudinal edges of the ring-carrying plates whereby they are held in pivotal relation with each other, and means on the outer longitudinal edges of the spring back plate for the reception and retention of the outer longitudinal edges of the ring-carrying plates.

5. In a device of the class described, opposed covers, a back portion connecting said covers, a spring back plate rigidly secured to said back portion, stop posts having crossheads rigidly secured in the opposite ends of said spring back plate, a pair of ring-carrying plates each having on its inner longitudinal edge adjacent one end thereof, a slot adapted to permit the passage therethrough of a portion of a cross-head on a stop post, one of said ring-carrying plates having another slot in its inner longitudinal edge, means on the inner longitudinal edges of the ring-carrying plates whereby they are held in pivotal relation with each other, means on the outer longitudinal edges of the spring back plate for the reception and retention of the outer longitudinal edges of the ring-carrying plates, and a locking tongue on the inner edge of one of said ring-carrying plates adapted to enter the second-mentioned slot in the inner longitudinal edge of the other ring-carrying plate.

6. The method of manufacturing a device of the class described consisting of forming a book body comprising opposed covers connected by a back portion, rigidly affixing on the back portion a spring back plate having stop posts carrying cross-heads in spaced relation rigidly affixed thereto, forming ring-carrying plates having means on their inner

longitudinal edges whereby they may be retained in pivotal relation with each other, and each ring-carrying plate also having on its inner longitudinal edge a slot adapted to receive a portion of the cross-head of a stop post, one of said ring-carrying plates being formed with a locking tongue on its inner longitudinal edge and the other ring-carrying plate being formed with a keeper slot on its inner longitudinal edge, placing the outer longitudinal edges of said plates in the opposite edges of the spring back plate, depressing said ring-carrying plates below the locking portions of the stop posts, and moving the ring-carrying plates longitudinally in relation to each other whereby the slots are moved from registration with the cross-heads of the stop posts to bring the plates beneath the cross heads, and the locking tongue is moved into registration with the keeper slot whereby the ring-carrying plates are secured against longitudinal movement.

7. In a device of the class described, opposed covers, a back portion connecting said covers, a spring back plate rigidly secured to said back portion, stop posts rigidly secured in opposite ends of said spring back plate, a pair of ring-carrying plates, means on the inner longitudinal edge of one of said ring-carrying plates for receiving and retaining in pivotal relation the inner edge of the other ring-carrying plate, each of the ring-carrying plates having on one end of the inner longitudinal edge thereof a slot having a shoulder adjacent thereto, and each of said plates having a shoulder at the other end thereof, one of said slots being adapted to register with and permit the passage therethrough of a portion of one of said stop posts and the other slot being adapted to register with and permit the passage therethrough of a portion of the other stop post, and said shoulders being adapted to be positioned beneath said stop posts when the ring-carrying plates are moved longitudinally in relation to each other.

8. In a device of the class described, opposed covers, a back portion connecting said covers, a spring back plate rigidly secured to said back portion, stop posts rigidly secured in opposite ends of said spring back plate, a pair of ring-carrying plates, means on the inner longitudinal edge of one of said ring-carrying plates for receiving and retaining in pivotal relation the inner edge of the other ring-carrying plate, each of the ring-carrying plates having on one end of the inner longitudinal edge thereof a slot having a shoulder adjacent thereto, and each of said plates having a shoulder at the other end thereof, one of said slots being adapted to register with and permit the passage therethrough of a portion of one of said stop posts and the other slot being adapted to register with and permit the passage therethrough of a portion of the other stop post, and said shoulders being

adapted to be positioned beneath said stop posts when the ring-carrying plates are moved longitudinally in relation to each other, a locking tongue on the inner edge of one of said ring-carrying plates, and a keeper slot in the inner edge of the other ring-carrying plate adapted to receive the locking tongue when it is brought into registration therewith.

In witness whereof I have hereunto set my hand this 29th day of Feb., 1928.

DON D. MYERS.
